FIG. 4

FIG. 5

FIG. 6

A. E. ANDERSON INVENTOR.

BY *Freeman A. Phillips*
ATTORNEYS.

UNITED STATES PATENT OFFICE.

ANDREW ELLIOTT ANDERSON, OF BROWNSVILLE, TEXAS.

GEOMETRICAL INSTRUMENT.

1,260,292.

Specification of Letters Patent. Patented Mar. 26, 1918.

Application filed December 26, 1916. Serial No. 128,812.

To all whom it may concern:

Be it known that I, ANDREW ELLIOTT ANDERSON, a citizen of the United States of America, residing at Brownsville, in the 5 county of Cameron and State of Texas, have invented new and useful Improvements in Geometrical Instruments, of which the following is a specification.

The present invention relates to improvements in geometrical instruments of the straight-edge type and involves the use of pivoted blades, as in a protractor, for laying out, measuring or protracting angles, etc.

15 The invention is designed to provide an instrument of this character having straight edges movable in the same plane and in such a manner that any angle between zero and 180° may be laid out, and either of which 20 straight edges may be made free and unobstructed from end to end in order that the drawing of a line from end to end of the straight edge is made possible, and also in order that the measuring or scaling of a line 25 by any suitable means found desirable is facilitated.

The invention consists in certain novel combinations and arrangements of parts as will be hereinafter described and claimed.

30 Figure 1 is a top plan view of my complete instrument.

Fig. 2 is a plan view of one of the blades detached.

Fig. 3 is a view in elevation showing one 35 blade in position, the base ring being broken away and the second blade omitted for convenience of illustration.

Fig. 4 is a detail plan view of a vernier plate.

40 Fig. 5 is a detail plan view of a clamp plate.

Fig. 6 is a sectional view, enlarged, on line 45 *a—a* Fig. 1, the section line also being indicated in the same manner in Figs. 2, 4, and 5.

In the preferred embodiment of my invention as illustrated in my drawings the instrument includes a pair of blades as 1 and 2, of metal or other suitable material, 50 and as arranged and combined with the other elements of the instrument each blade is fashioned with a pair of parallel straight edges, the inner edges of the blades being indicated by the respective numerals 3 and 4 and the outer edges of the blades being indicated by the numerals 5 and 6. The

blades 1 and 2 are movable in the same plane and adapted to swing about the same center, with the inner ends of the inner straight edges always in contact as at the point or 60 corner 7 in Fig. 1, and the movement of the blades permits them to be turned or swung from a point of coincidence with the two edges 3 and 4 in parallelism and in contact, to measure or lay out between them any 65 angles up to an angle of 180°.

The two blades are combined with the base ring 8 which is a graduated, circular, open center plate, preferably of metal, and the two blades may be swung or revolved 70 about the ring and held in adjusted position by means of a set of plates 9 and 10 and 9' and 10' respectively. The base plates 9 and 9' are each provided with a circular groove 12 coincident with the base ring 8, and as 75 the base plates are provided with a vernier, as shown I will hereinafter call them the vernier plates or grooved vernier plates to distinguish them from their complementary plates of resilient metal 10 and 10' which 80 are the clamp plates for holding the blades in adjusted position. The vernier plates and the clamp plates are secured to the blades by means of screws 11 passing through both plates and the respective 85 plates, and each pair of plates is provided with a fixed screw bar as 13 and 13' fixed in the respective blades and passing through openings or perforations in the pairs of plates. Each of the screw bars has a clamp 90 nut as 14, 14' threaded thereon and the nuts bear upon the upper face of the clamp plates, so that by properly turning these nuts it will readily be seen that the ring 8 may be clamped or clasped and held between 95 the pairs of plates, thus rigidly holding the blades with relation to the base ring 8. Each of the clamp plates 10 and 10' is fashioned with a notch or recess as 15 and 15' and these notches are adapted to engage the 100 respective pins 16 and 16' in order to limit the movement of the blades on the base ring. When the two inner ruling edges are fitted together it will be seen that the pins will be engaged in the notches and in this position 105 the verniers on the plates 9 and 9' are automatically set at zero or first graduations from the ends of the base ring, the clamp plates being cut away in order that the verniers on the plates and the scale on the 110 ring may be read with facility.

It will readily be seen that both blades

may be swung about a point in the axis of the base ring to adjusted position, and the operator may secure an open and unobstructed inner ruling edge 3—by setting the vernier plate 9 with the vernier at O and turning the required angle at vernier of plate 9'. Or an open and unobstructed ruling edge 4 may be secured by setting the vernier plate 9' at O and turning the required angle at vernier 9. Thus the instrument is specially adapted for conveniently platting of deflection angles and for the protracting on a map of all angles in the same manner as they were measured or turned with a compass or transit. One of the blades of course may be temporarily fixed and the other blade used for determining angles, and of course the blades may be swung around into longitudinal alinement with each other, with the point 7 always a contact point between the blades, and the presence of the break or space between the ends of the base ring provides for a continuous ruling edge 3 or 4 as desired. The outer ruling edges, when used in connection with the usual parallel ruler, are specially adapted for the platting of maps or mapping of field notes by bearings or azimuths.

What I claim is:—

30. 1. In a geometrical instrument, the combination with a graduated ring, of a pair of blades movable with respect to said ring and a vernier scale carried by each blade, said

blades having ruling edges adapted to be disposed at different angles to each other, 35 the two plates always contacting at a point in alinement with said ruling edges and coincident with the center of the ring.

2. An instrument comprising a graduated base ring, a pair of blades movable with 40 respect to said ring; a grooved vernier plate on each ring adapted to receive the ring into the groove thereof and to coöperate with the graduations thereon, and a clamp plate secured to each vernier plate for locking the 45 parts in adjusted positions.

3. An instrument comprising a graduated base ring, a blade movable with respect to said ring and having a grooved plate fixed thereon adapted to receive the ring into the 50 groove thereof and to coöperate with the graduations thereon, a clamp plate secured to the grooved plate and blade, and means for clamping the plate and ring in adjusted positions.

4. The combination with a blade having a grooved vernier plate and a resilient clamp plate fixed thereon, of a base ring provided with graduations and located between said plates, a screw bar fixed to the blade and 60 passed through the plates, and a nut on the bar for clamping the plates to the ring; said blade being movable with respect to said ring.

In testimony whereof I affix my signature. 65
ANDREW ELLIOTT ANDERSON.
